United States Patent Office.

CHARLES L. STEVENS, OF GALESBURG, ILLINOIS.

Letters Patent No. 60,803, dated January 1, 1867.

IMPROVED WATER ELEVATOR FOR RAILROAD TANKS.

The Schedule referred to in these Letters Patent and making part of the same.

TO ALL WHOM IT MAY CONCERN:

Be it known that I, CHARLES L. STEVENS, of the city of Galesburg, in the county of Knox, and State of Illinois, have invented a new and improved Mode of Elevating Water into Railroad Tanks; and I do hereby declare the following to be a full, clear, and exact description of the construction and operation of the same, reference being had to the accompanying drawings, making a part of this specification, in which—

Figure 1 is a plan view of a rail platform, track, levers, and weights.

Figure 2, an end view of the platform and track, showing side view of levers and weights.

Figure 3, side view of track and platform, showing ends of transverse beams with friction-rollers at their ends, in vertical openings, in bed-sills.

Figure 4, side view of plate as constructed and attached to the side of the rail of the platform.

Like letters in all figures of the drawings indicate like parts.

The nature of my invention consists in constructing the rail platform with three transverse beams, having shaft rods passed through the same, and with friction-rollers on the ends of them. The said shaft rods; with the rollers thereon, projecting into suitable vertical openings into bed-sills under the rails attached thereto, to serve as guides in the movement of the platform: the centre of the transverse beams of the platform resting directly on three friction-rollers attached to the ends of three levers so arranged that by the passage of cars over the platform, and by means of weights connecting with the levers, that three pumps may be operated on simultaneously by the action of the platform thereon; the construction of the levers with friction-rollers on the ends of them, giving an easy movement to the platform, which, as has been found, renders this method the most simple, practicable, and less expensive than any known method discovered heretofore. My invention has reference further to constructing the outer beams of the platform with friction-rollers to serve as lateral guides against the bed-sills in the depressing and elevating movement of the platform; also, in the construction of the plates on the sides of the rails of the platform, so as to attain solidity, strength, and durability, as to withstand the frequent contact of the wheels and the weight of the cars thereon. It will be observed that my invention is intended as an additional improvement to that heretofore patented by me.

To enable others skilled in the art to make and use my invention, I will proceed to describe its construction and operation.

The rails, A, are constructed with side plates, a, suitably attached thereto, (see fig. 3,) which rails and plates form the sides of the platform, being secured in a substantial manner to three transverse beams, b, which beams constitute the framework of the platform, (see same in dotted lines in figs. 1 and 2.) The beams are planked tightly thereon, which planking is secured thereto, between the rails, in a proper manner; the platform as thus weather-tight constructed protecting the machinery connecting therewith, underneath, from the elements. Passing through the beams in a suitable manner, are shaft rods, which project sufficiently from the sides of the platform to receive the friction-rollers, c, thereon. The two outer levers, C, converge inwardly from the bed-sill to the centre lever, C', (see fig. 1,) and are supported by fulcra, d. At the ends thereof are rods, e, (see fig. 2,) which are supposed to represent the piston rods of the pump or rods connecting therewith. The levers extend from the pumps to and through the side of the bed-sill, and project therefrom to about midway between the sills D, (see figs. 1 and 2.) Attached to the levers in a suitable manner are weights, E, of the proper size, (see figs. 1 and 2,) which are supposed to be suspended therefrom over the well for supplying the tank with water, into which well the pumps are placed: The levers have their ends constructed with friction-rollers, f, arranged properly thereon; the ends of which levers are elevated sufficiently from the points of their connection with the pumps by the fulcra, to give the proper depressing and elevating movement to the platform when the cars are passing over the same, which platform, as herein described, is placed between the track rails F at the point desired, and made to rest directly on the friction-rollers of the levers by means of the transverse beams; the friction-rollers of the shaft rods of the beams being placed immediately under the track rails into suitable vertical openings, g, (see same in dotted lines in fig. 3,) mortised out on the inside of the bed-sills. A sufficient excavation of the ground between the track rails is first made before the platform is fixed, to give the required room to the operation of the levers underneath the same. The bed-sills are secured on the sides of the excavation and below in the

most substantial manner. The levers above remarked are placed below the surface of the track and operate through the sill as herein described. The bed-sills are cut down vertically about half of the thickness of the sill or thereabouts, to receive the platform. The vertical openings, as mentioned, to receive the friction-rollers of the shaft rods, are thence mortised out on the cut side of the sill. The object of the side plates constructed on to the rails of the platform is not only to attain strength and durability, as remarked, but is to keep the sides of the platform close, so as to render it impossible for any maliciously disposed person to insert anything between the sides of the platform and the track rails calculated to throw the cars off from the same; the track rails being so constructed on the edges next to the side plates of the platform, as to give a close fit, and at the same time sufficiently loose as to allow a free movement to the platform. On the corners of the outer beams are plates suitably arranged with friction-rollers, *h*, which rollers serve as lateral guides against the sides of the sills to keep the corners of the platform from catching on to the same on being depressed, and thus allow the corners or ends of the platform to rise uniformly to its proper relative position to the track rails. The friction-rollers of the shaft rods, as will be observed play or operate into the vertical openings in the bed-sill on the curved and straight sides thereof, which serve to give an easy and steady movement to the platform. On the platform being depressed, and upon its rising, the friction-rollers are brought up, under, and against the track rails, thus preventing the platform going any further, which arrangement gives it proper relative position to the track rails upon every ascending movement of the platform.

Operation.

A train of cars when arriving on the platform causes an easy depressing movement thereto, by virtue of the friction-rollers in their connection with the levers operating under the beams, which movement is imparted correspondingly to the levers; the weights attached thereto being counterbalanced by the weight of the cars of the train on the platform, this movement causing the ends of the levers to ascend, which gives the upward stroke to the rods of the pump; each truck of the car giving an upward stroke, and the weights elevating the platform to its proper position above the track rails upon the immediate departure of each truck therefrom, giving the downward stroke to the rods of the pump, and so on alternately.

Having thus fully described my invention, what I claim therein as new, and desire to secure by Letters Patent, is—

1. The arrangement of the three levers *C C' C*, constructed with friction-rollers *f* on their ends for operating the pumps by the depressing and elevating movement of the platform beams *b*, resting directly thereon, and weights *E* connecting therewith, substantially in the manner and for the purpose as set forth.
2. I claim weather-tight planked rail platform resting directly on the friction-rollers *f*, of the ends of the levers *C*, substantially in the manner and for the purpose as set forth.
3. I claim the platform beams *b*, having shaft rods constructed with friction-rollers *c* on their ends, and operating in vertical openings *g*, in the bed-sills *D*, and under the rails, substantially in the manner and for the purpose as set forth.
4. The friction-rollers *h*, as arranged on the corners of the ends of the platform to serve as lateral guides in the depressing and elevating movement of the platform, substantially in the manner and for the purpose as set forth.
5. The weights *E*, as arranged in their connection with the levers, substantially in the manner and for the purpose as set forth.
6. The side plates *a*, on the sides of the rails *A* of the platform, substantially in the manner and for the purpose as set forth.

CHAS. L. STEVENS.
